UNITED STATES PATENT OFFICE.

JOHN GLEN NEWMAN, OF MILSON'S POINT, NEAR SYDNEY, NEW SOUTH WALES,
AUSTRALIA.

IGNITING DEVICE FOR INTERNAL-COMBUSTION ENGINES.

1,084,815.

Specification of Letters Patent. Patented Jan. 20, 1914.

Application filed December 16, 1912. Serial No. 736,914.

To all whom it may concern:

Be it known that I, JOHN GLEN NEWMAN, subject of the King of Great Britain and Ireland, residing at 7 North Cliff street, 5 Milson's Point, near Sydney, in the State of New South Wales, Australia, have invented a certain new and useful Improved Igniting Device for Internal-Combustion Engines, of which the following is a specification.

10 My invention relates to that type of device for producing sparks for igniting the charge in an internal combustion engine wherein the spark is struck at the proper firing time intervals by the frictional contact 15 of an abradant surface upon a piece of pyrophoric material.

The object of the invention is to provide a certain construction of device of the type mentioned wherein the necessity for replacing 20 the pyrophoric material frequently is avoided by forming the same in a special shape which presents an extensive surface to be acted on by the striker and using a special form of striker, whereby a large 25 body of material is rendered available and an extended life of a single charge of pyrophoric material is thus procured. In carrying out my said invention the pyrophoric material is molded in the form of a hollow 30 cylinder and the striker acts against the end of said cylinder, sector by sector, as the parts are moved relatively to each other at proper firing time intervals. Such a hollow cylinder will contain a body of pyrophoric 35 material equal to the bulk of many pencils such as are used in other constructions of such apparatus. In the preferable form of the abrading device or striker said device consists of a disk having two offsets on its 40 end, one of which is a smooth face sector of hard metal which acts as a gage and the other an insert of a slow wearing abradant, such for instance as hard emery or carborundum, or a jewel. In the other form a jewel 45 or scratch point of hardened metal or of carborundum, emery or like hard substance is carried in the end of a holder, and acts against the end of said hollow cylinder making contact with the same, sector by sector, 50 as the parts are moved relatively to each other.

In the accompanying drawings, Figure 1 is a sectional elevation. Fig. 2 transverse

sectional elevation showing the disk form of striker with gage; Fig. 3 sectional elevation 55 showing the jewel point form of striker; Fig. 4 transverse sectional elevation showing the operative relation of the jewel striker to the pyrophoric cylinder; Fig. 5 semiidiagrammatic view showing mechanism 60 for moving the striker or the pyrophoric cylinder; and, Fig. 6 detail view of the spark advancing and retarding mechanism in connection with the striking cam by which the mechanism is operated. 65

In the case of either construction, the pyrophoric material is molded into the shape of a hollow cylinder 1. In the arrangement shown in Fig. 1 this hollow cylinder is fixed in the forward end of a sliding carrier 2 70 which is pressed forward by a helical spring 3 setting back against the cap 4, which cap is fitted with wings 5 to enable it to be screwed at 6 on to the pocket extension 7 of the plug 8. 9 is an offset pin or sinking 75 slidable in a slot 10 to hold the sliding carrier 2 against rotation in the pocket 7 while permitting it to slide inward therein under the pressure of the spring 3. In this construction the striker consists of a disk 11 80 mounted on the end of spindle 12. At one part of the face of this disk there is an offset piece 13 polished on the face which rubs against the end of the pyrophoric cylinder 1 and acts as a gage for the striker insert 14 85 which is a piece of hard emery, carborundum, or steel with a roughened face or other suitable abradant. The operating mechanism, which is separately described below, acts to partially rotate the shaft always in 90 one direction at proper timing intervals, thereby causing the abradant insert 14 to rub over a sector of the pyrophoric cylinder 1, and in so rubbing to strike a spark.

In the arrangement shown in Fig. 3, the 95 pyrophoric cylinder 1 is mounted on a fixed carrier 15, the stem of which is fixed in the back nut 16, said nut being screwed at 17 into the casing 18, wings 19 being provided to facilitate removal. 20 is a pocket in alignment with one side of the pyrophoric cylinder 1. In this pocket there slides a carrier 21 acted upon by a helical spring 22 in compression, 23 being a back end cover taking against the end of said spring. When this 105 cover 23 is removed the spring 22 and car-

rier 21 and also the abradant striker 24 which is fixed in the forward end of the part 21 may be withdrawn and replaced. The abradant 24 may be hard carborundum or emery or a jewel or a serrated end of hard steel. The operating mechanism is in this case fitted on the spindle 25 which carries the pyrophoric cylinder holder 15. This mechanism separately described operates to move 10 the pyrophoric cylinder 1 through a certain arc of rotation at proper timing intervals causing a spark to be emitted at the point of contact of the abradant 24 at the end of said cylinder at each movement. 36 is a 15 shoulder piece which carries the nave 37 of the rocking arm 38. The rear end 39 of this rocking arm carries a pawl 40 on a pin 41. A light spring 42, the body end of which is fixed in the hole 43 in the rocking arm 20 bears on the back of the pawl 40 and keeps same in contact with the detents on the edge of the wheel 44. This wheel is keyed on the outboard end of the spindle 12 and said spindle moves in its bearing with a little 25 friction. The rocking arm 38 carries a tappet piece 47 which is acted upon by the pawl or cam 48 on the collar 49. This collar is slidable endwise on the half time shaft 50 of the engine and a helical feather way or 30 key 51 on said shaft coacts with the complementary part of the collar 50, so that when said collar 50 is moved lengthwise of the shaft it is turned relatively to the shaft. This endwise movement of the collar is 35 effected by means of a fork, not shown, which engages the groove collar 55. A spring 56 is provided to hold up the outboard end of the rocking arm 38 to any fixed part of the engine structure.

What I claim as my invention and desire 40 to secure by Letters Patent is:—

1. An igniting device for internal combustion engines comprising a hollow cylinder of pyrophoric material, a striker bearing lightly against the end of said cylinder, 45 and means for effecting relative movement of said cylinder and striker while maintaining them in light frictional contact.

2. An igniting device for internal combustion engines, comprising a hollow cylinder of pyrophoric material, a striker in light frictional contact therewith and means for moving said striker at firing time intervals 50 over the end of said cylinder.

3. An igniting device for internal combustion engines consisting of a hollow cylinder of pyrophoric material held in a slidable but nonrotatable inclosed carrier, a striker disk having on its face a gage offset and a 55 striker offset of abradant material, and pawl and detent operating mechanism acting on the spindle of said striker disk, actuated by the engine, and operating to partially rotate said striker disk at firing time intervals. 60

4. An igniting device for internal combustion engines comprising a hollow cylinder of pyrophoric material, a striker, means 65 for holding said striker against the end of said cylinder, and means for effecting the relative movement of said cylinder and 70 striker without interrupting the operation of said holding means.

In testimony whereof I have affixed my signature in presence of two witnesses.

JOHN GLEN NEWMAN.
